LOOM TRANSFER MECHANISM

Joseph Stuer, Lawrence, Mass.

Application July 30, 1945, Serial No. 607,816

8 Claims. (Cl. 139—243)

1

This application is a continuation in part of application for United States Letters Patent by Joseph Stuer on Stationary magazine loom, filed September 2, 1943, Serial No. 500,947.

That application and this show a device or devices applied to a bobbin changing loom using one or more shuttles and having a reserve bobbin magazine and either one shuttle box or vertically shifting shuttle boxes under the magazine, transfer mechanism and a weft feeler. The devices covered in this application are part of a transfer mechanism which includes a hammer arm and a head for forcing a full bobbin to take the place of an empty bobbin in a cell or a shuttle box, and a dog arm to which a dog is pivoted in such a position that when it is moved in front of a bunter carried by the lay, this transfer dog and arm are pushed forward near front center whereby the hammer arm with its head is carried down onto a reserve bobbin thus effecting transfer of this bobbin into a shuttle.

The particular feature of this application is the mechanism for positioning the transfer dog to engage the bunter when the feeler, preferably of the electrical type, indicates near exhaustion and closes the circuit to a solenoid or magnet which pulls a spring locking pin, or equivalent member, which ordinarily holds the dog in inoperative position, but which pin when pulled against its spring by the solenoid allows the dog to assume either by the force of a spring or by gravity, its operative position with its free end in the path of the bunter.

Preferably I accomplish this by interposing a solenoid carried by the stationary frame of the loom and connected by a flexible member, such as a chain, with such a pin so that when the solenoid is energized by the action of the feeler, this pin is pulled out from in front of, behind, or out of engagement with the transfer dog arm allowing the dog to move or to be moved on its pivot. Preferably this pin is normally spring pressed and, instead of engaging behind the dog arm, it might engage a hole or recess in that arm but in any case after transfer its spring will cause it to resume its holding or locking position.

This spring locking pin is carried by a dog controlling member carried by the dog transfer arm and is so associated with the dog as to compensate for the variations in the path of movement of the dog pivot, of the free end of the dog, and of the bunter, all of which could move in different paths.

In said application, I show a dog so pivoted

2

and weighted that its free end is normally held in a position above the path of the bunter but which, when released by pulling a spring locking pin, drops by gravity or by spring action into the path of the bunter or into operative position.

However, as in some looms there is little room above the path of the bunter and the action of gravity is initially slow, I show another and preferred embodiment of my device in which the free end of the dog is normally held below the path of the bunter but when the pin is pulled to release the dog, the dog is instantaneously moved up into position by a dog setting spring.

Advantages of this device in its various embodiments are that the devices for positioning the dog in the path of the bunter are all carried by the dog holding transfer arm, except for a connection, which is preferably flexible, to a solenoid or similar electrical device which is energized by closing an electric circuit through a feeler.

The whole control is thus very much simplified and is not dependent upon the action of any cutter or other mechanism thus allowing such cutter or other mechanisms to be operated without reference to the dog and bunter.

With my preferred construction operable by a dog setting spring, the dog is instantly snapped into position so that it is possible to have the feeler located at the back of the loom under the magazine, the time interval between back and front center being enough to allow the spring to snap the dog into its transferring position.

It is obvious however that the feeler might be located in any position desired such as on the non-magazine side of the loom, at the front, or even above or below the box in which is the shuttle with the bobbin to be felt for indication and transfer. It is also clear that this quick cooperation between the feeler and the dog could be utilized in a magazine loom of any type such as of the single shuttle, single box type, multiple shuttle, or multiple box type.

The main idea of my device is to simplify the control of the dog and I do this by using a controlling member which may be of various kinds for various looms of different sizes and to accommodate different spaces. In all cases, the dog or device which is engaged by a bunter on a loom is freely pivoted on the dog holding arm of a transfer device of a well known type and it is held out of reach of the bunter by a dog controlling device which in whole or in part is operable by an electric feeler and solenoid wherever on transfer some part of, or the whole con-

trolling member, is released allowing the dog to drop into position by gravity or allowing it to be raised, lowered or to be moved sideways.

Such a member may include a projection from the dog including a pin which when it is pulled out the dog drops by gravity; it may include an arm fixed to the dog carrying arm of the transfer which carries a spring arm with a hook on its end which normally holds the dog up out of the way; it may consist of a spring between the parts of a two part dog, one part pivoted on a horizontal pivot to the transfer arm and the other part pivoted to it on a vertical pivot, the solenoid being connected directly with that part of the dog which is to engage the bunter to pull it into position against such a spring which may be called the controlling member.

Preferably I use a dog controlling member which is pivoted on the same pivot with the dog on what I call the dog pivot shaft and which at times can move independently of the dog and which normally includes a spring latch pin which when pulled against its pin spring by the solenoid allows the dog to be dropped or causes it to be lifted as will be described.

Throughout the specification and claims I use the term "arm" as applied to the member on which the dog is freely pivoted, although as shown in the drawings it ends in two members between which the dog is carried, because in some looms, this dog carrying arm starts as a single member and ends in a fork with two prongs and it is really one bifurcated arm.

For clearness I mean by "transfer" or "transfer hammer" the device pivoted to the loom frame which is substantially a bell crank lever with two arms, one to carry a head to engage a full bobbin and the other to support a dog.

In the drawings,

Fig. 1 is a diagrammatic side elevation of part of an automatic loom of the stationary magazine type showing part of the frame and part of the lay, the front of the loom being shown as at the left and some parts being broken away, the bobbin transfer hammer with its arms and the dog being shown in their usual, normal or inactive position.

Fig. 2 is a diagrammatic view of the feeler and its electrical connections with the solenoid.

Figs. 3, 4, 5, 6, and 6A with parts omitted show one embodiment of my device.

Fig. 3 is a side elevation of the transfer hammer arms, dog and connections together with the bunter and part of the lay, showing the dog in full lines after it has dropped into operative position in the path of the bunter.

Fig. 4 is a view similar to Fig. 3, but showing in full lines the parts at or near front center, the controlling member being shown in the position it assumes when it is reset, the dog stop being omitted.

Fig. 5 is a detail side elevation enlarged, showing in full lines the usual position of a dog and its controlling member, and in dotted lines, the position of these parts after indication but before transfer.

Fig. 6 is an enlarged elevational view as from the left of Fig. 3, with the dog and associated parts in operative position.

Fig. 6A is a detail view partly in section as from the front showing the dog holding pin member in position where it holds the dog in its inactive position.

Figs. 7 to 11 show another and preferred embodiment of my invention.

Fig. 7 is a view similar to Fig. 1 and Fig. 5 with the dog and its controlling member shown in full lines as inactive.

Fig. 8 is a view similar to Fig. 4 showing in full lines the parts as at about front center with the controlling member reset and before the dog has dropped.

Fig. 9 is a detail view similar to Fig. 5 of the dog, dog controlling member and resetting parts in inactive position with parts broken away for clearness.

Fig. 10 is an isometric view of the dog controlling member.

Fig. 11 is a view similar to Fig. 6 as from the left of Fig. 7.

Fig. 12 is a detail view of a modified form of the spring pressed, dog holding pin.

Fig. 13 is a side elevational view similar to Figs. 1 and 7, showing the application of the device to a rotary magazine or battery loom, the dog controlling mechanism being that shown in Figs. 7 to 11.

Fig. 14 is a diagrammatic detail view like Fig. 5 of an embodiment similar to that shown in Fig. 1, the view showing in full lines the transfer arms, dog and other parts in their inactive and in dotted lines their active position and Fig. 15 is a similar view showing the parts in the position that they assume when reset and transferring at front center.

Fig. 16 is a detail plan view showing another modification of the dog controlling means and Fig. 17 is an elevation of the construction shown in Fig. 16.

Figs. 18, 19, 20 and 21 show still another modification of the dog controlling means, Fig. 18 being a view showing in full lines and Fig. 19 being a view as from the right of Fig. 18.

Fig. 20 shows the transfer arms with the dog and dog controlling means, together with the bunter part way between back and front center and Fig. 21 shows these same parts at substantially front center.

In Figs. 1 to 6A, I show the construction described in my said application filed September 2, 1943, Serial No. 500,947, as far as that shows and applies to the dog controlling means.

In all the drawings, L indicates the frame of a bobbin changing loom.

There may or may not be a plurality of shuttles P, P, and vertically shifting shuttle boxes such as B. Each box might have a plurality of cells II or a single cell.

M indicates a magazine which, as shown, is of the multiple stack type each stack 1, 2, 3, 4, including a plurality of bobbins such as A. A. On the lay 6, is a bunter 5 of the usual form and pivoted on the frame L at 80 is a transfer hammer H which has two arms 12 and 13, one 12 carrying the usual head 14 for contact with a bobbin A on transfer and the other 13, having bearings 70 for a dog pivot shaft 16 which carries control member or latch N, and dog 15. 9 is the usual transfer spring. Z represents give-ways.

F indicates a feeler of the electrical type shown as positioned at the back of the loom frame, although it might be located in any other position, the feeler being provided with a contact switch 40 which, when its finger 48 slips on an almost exhausted bobbin, closes a circuit through the wires 41 and 42 from a source of electricity such as a battery 43 through a solenoid S. This solenoid S has a core 44 connected by a wire 45 to a spring lock pin 46 which passes through and

is slid able in a spring lock pin hole 111 through a pin arm 120 of a dog controlling member or latch N. 47 is the spring for the lock pin 46.

This dog controlling member N is carried on or preferably by the dog pivot shaft 16 on which the dog 15 is loosely pivoted and is connected to dog 15 by an elastic member 118. The pivot 16 of both is so placed and the weight is so distributed that member N and dog 15 will drop to the position shown in full lines, Fig. 3, if not held back by pin 46.

Dog 15 also has a stop arm 18 which carries an adjusting stop screw 71 to limit the distance of the drop and to position the free end of dog 15 in the path of bunter 5.

Under ordinary circumstances, the pin 46 on account of the action of its spring 47 and when the solenoid is not energized has one end projecting from its hole 111 in front of the dog holding arm 13, as shown in Figs. 1, 5 and 6A.

In this embodiment and when the pin 46 is pulled by the energizing of the solenoid so that its end clears arm 13, gravity allows the controlling member N, connecting spring 118 and the dog 15 to drop down from the position shown by the dotted lines to the full line position shown in Fig. 3, so that dog 15 will be engaged by bunter 5 when the lay moves forward.

In Fig. 6, I show at one end of dog shaft 16 a holding collar 72 with a set screw 73 and there might be a similar collar at the other end but I combine such a collar with the dog controlling member N shown as adjustable by a set screw 74 and also serving to keep shaft 16 from slipping out of place.

As the arm 119 or movable resetting member of dog controlling member N is directly in line with pin arm 120, it does not show in Fig. 6, but it alone supports follower 117 which extends back of the arm 13 over until it is in line with the fixed guide or resetting member 116 on which follower 117 rides for resetting.

The operation is shown in Figs. 3, 4, 5. Starting when the feeder F indicates near exhaustion, the solenoid S pulls the pin 46 of the controlling member N against spring 47 so that its projecting end is clear of arm 13 allowing gravity to drop the member N, connecting member 118 and therefore dog 15 to a point in front of the bunter 5, Fig. 3, full lines, where when the bunter 5 goes forward it engages the free end of the dog 15, which pushes the dog forward, arm 12 down and head 14 down on a bobbin A which is forced into the shuttle.

The closing of the electrical circuit by the feeler F is instantaneous and the moment the pin 46 is pulled in, the dog is dropped down into position by gravity. A spring might be used to assist gravity. Latch N also drops.

This forward motion of the bunter 5 and the pivotal motion of the arm 13 and dog 15 also move back the controlling member N until the end of pin 46 is forced out by its spring 47 in front of the arm 13 thus again locking the dog away from the bunter until the next indication.

As the transfer hammer H with its spring 9 is pivoted at 80 on the frame, while the dog 15 is loosely pivoted on the dog pivot shaft 16 on the dog arm 13 and the bunter 5 moves forward with the lay on a flat arc and pushes the dog with it, as shown in Figs. 3 and 4, I find it desirable to have an elastic connection 118 between the dog 15 and member N to allow the dog to move on a flat arc and the dog controlling member N to be

so moved that pin 46 can snap into position in front of arm 13.

The dog and member N are both pivoted at 16 on dog arm 13 and I therefore provide an elastic connecting member 118 between the control member N and the dog 15 which can yield but tends to pull them together.

The controlling member N has one pin carrying arm 120 through which is a pin hole 111 for pin 46 but also has another or resetting arm 119 at the end of which is a follower 117 which extends out so as to engage a fixed guide 116 and to ride up on it thus moving the pin carrying arm 120, with the pin 46, forward along the side face of arm 13 so that the spring 47 for pin 46 can snap its end out in front of the dog arm 13 when that arm moves forward on transfer, thus holding member N in place but allowing the free end of dog 15 some freedom of movement. See Figs. 3 and 4.

While so held, this controlling member N through the spring 118 allows the free end of the dog 15 to follow the bunter 5 back separating from the arm 119 as shown by the full lines in Fig. 4, until the bunter 5 leaves the dog as the lay recedes when spring connection 118 snaps the end of the dog up into its normal position as shown by the full lines in Fig. 5. When the pin 46 is again pulled out by the solenoid, the dog and the controlling member N again drop by gravity down into transferring position as shown by the full lines in Fig. 3. The dotted lines in Fig. 3 show the up or normal position of the dog 15 and controlling member N when held up by pin 46 and spring 118 during the time between transfers.

When the bunter releases the dog, spring 9 returns transfer H to the position shown by full lines in Figs. 1, 3 and 5.

Another and preferred embodiment of my invention is shown in Figs. 7 to 11. In these views L represents the frame; P a shuttle; B a shuttle box; M a magazine; A a bobbin; S a solenoid; and F a feeler; all the same as in the first described construction.

The transfer hammer H has the arm 12 and head 14 but the other arm to which the dog 15 is pivoted is indicated by 23 and is similar to 13 and, as shown, it is bifurcated. It has bearings 126 similar to 70 for a dog pivot shaft 26 similar to 16 except that this shaft is turnable in the bearings 126 while 16 may or may not be so turnable.

In place of the dog control member or latch N, I use in this case a member C which has a pin arm 20 through which is a hole 21 for a spring lock pin 22 normally urged by spring 24 to project so that it can go in behind of, instead of in front of, the dog transfer arm 23. By means of a flexible member or chain 25, it is connected to the armature of the solenoid S as in the other construction.

Member C has an arm 30 which I will call a stop arm as it has a laterally projecting web 31 which extends in front of arm 23 and limits the pivotal motion of member C by engaging the front of arm 23.

There is a third arm 35 which extends down and engages the front or heel 19 of dog 15 and carries a set screw 36 by which the position of the dog 15 can be adjusted.

The normal or between transfers position of dog 15 is shown by the full lines in Figs. 7 and 9, with its free end below the bunter 5.

There is also a dog setting tension spring pin 37 in member C to which one end of a dog setting

tension spring 38 is connected, the other end of spring 38 being attached to another pin 39 on some part of the frame L. The position of this pin 37 on member C and the position of pin 39 on the frame are such that spring 38 tends to move member C so that arm 35 and set screw 36 will push against the heel 19 of dog 15, thus lifting the free end of the dog as shown by the dotted lines in Fig. 7, in front of the bunter 5 where it may be positioned by a stop 125.

This dog 15 is freely mounted on dog pivot shaft 26 but member C is fixed thereto and there is also fixed thereto a resetting arm 50 which moves with member C and the shaft 26 and is so positioned, as by a set screw 53, that when transfer dog arm 23 is in its usual position and the pin 22 of arm 20 is engaging the back of arm 23, arm 50 is out of contact with a stop 51 fixed to the frame L. Arm 50 is also out of contact with or just touching stop 51 when pin 22 is first released so that the parts are in dotted line position shown in Fig. 7 and when lock pin 22 is bearing against the side of transfer dog arm 23. However as bunter 5 moves forward with the lay, and pushes the dog 15 with its arm 23 forward, this resetting arm 50 engages the stop 51 with the result that it holds the end of pin arm 20, where release pin hole 21 and pin 22 are located while dog arm 23 is moving forward until the pin 22 springs into place behind it as shown in Fig. 8.

During this holding period, the heel 19 of the dog 15 is disengaged from the set screw 36 and, the dog 15 being limited in its upward movement as the lay beats up by fixed stop 125 if necessary, the dog 15 and its controlling member C move independently, coming together as shown in Fig. 8, instead of separating as do dog 15 and member N of the first construction, while the free end of the dog and of the bunter are moving together and moving the transfer dog arm 23 and transfer H to replace an empty bobbin with a full one.

As shown in Fig. 9, arm 50 is directly in line with arm 20 but as it is preferably adjustable by means of set screw 53 as shown in Fig. 10, it can be more nearly in line with stop arm 30, the fixed resetting member such as 51 being made shorter as shown by the dotted lines in Fig. 7.

As shown in Fig. 12, the spring locking pin and its spring can be combined as a spring hook K, the part 60 serving as a locking pin and the part 61 being the spring.

This also shows that a locking pin such as 60 instead of engaging either the front or back of the dog arm of the transfer might enter a pin hole 62 near its front or back.

Either embodiment shown herein can be used in connection with a rotary magazine or battery such as G. I show in Fig. 13, a rotary battery G of a well known type with a dog 15 pivoted to a dog arm of the transfer hammer H, a dog control member C which is resiliently connected with the dog and which carries a spring lock pin 22 which normally locks the control member C of the dog so that the free end of the dog is below the path of the bunter 5, the lock pin being flexibly connected with a solenoid or a similar device which is energized by an electrically operable feeler which closes a circuit to the solenoid when the feeler moves so as to indicate exhaustion.

Z, Fig. 1, represents the giveways or the usual means to receive a full bobbin which has been released from a stationary magazine and to hold it in position to be transferred into a shuttle box on the lay.

As magazine or battery G, turns in a well known

manner, it does not need giveways such as Z as, after each transfer, it moves another full bobbin into position to be transferred.

It is clear that with a rotary battery, instead of the second embodiment where the dog is lifted by a spring, the first embodiment, where the dog and its dog controlling member N drop by gravity, could be used and it is clear that the various arms could be provided, if necessary, with additional adjusting screws.

For convenience, I will call the resetting arm 49 with the follower 117 a movable resetting member and guide or member 116 a fixed resetting member as these terms describe similar devices in both embodiments shown.

The dog controlling member such as N or C includes a spring actuated locking pin such as 46, 22 or 60; a movable resetting member such as 119 and 117 or arm 50 and a fixed resetting member such as 116 or 51.

The member connecting a locking pin such as 46 or 22 with a solenoid should preferably be flexible but, depending on the distance, it might be a link such, for instance, as shown at 45 in Fig. 6.

As the arms 119 and 120 of the construction shown in Figs. 1 to 6A are integral with the number N, that member N as well as the dog 15, might be pivoted free on the shaft 16, but, as shown in Fig. 10, the similar members 20 and 50 of the construction shown in Figs. 7 to 11 must move with instead of on the dog pivot shaft 26.

The preferred constructions here described require resetting devices of a character which will admit a certain amount of freedom between the dog and its member as the lay advances after the bunter engages the dog but will reset the parts for the next transfer.

A simplified construction wherein the dog 15 is fixed directly on the dog shaft 16 which is turnable is shown in Figs. 1, 14, and 15. In that case there is a controlling member X like N also fixed to dog shaft 16 in which is the pin 46 but, as shown in all three views, the path of the bunter 5 as it forces the dog and its pivot shaft forward is such that this dog controlling member fixed to the dog shaft is so moved from the position shown in Fig. 14 to that shown in Fig. 15 that the pin 46 at front center springs back into place in front of the dog carrying arm 13. When pin 46 is pulled, dog 15 drops to the dotted line position shown in Fig. 14.

In Figs. 16 and 17 I show a dog in two parts 161 and 163 part 161 being pivoted at 162 to the dog arm 60 on a horizontal pivot and the part 163 being pivoted to the part 161 on a vertical pivot 164, there being a spring 65 between the parts 161 and 163 which tends to keep the part 163 away from the bunter 67 as shown in Fig. 16 but when it is pulled by a connecting member from a solenoid S, it is engaged by the bunter and is not released until the bunter lets go of it when it springs sideways to its usual position shown by full lines in Fig. 16.

In Figs. 18, 19, 20, and 21, I show an arm 81 extending backward from the dog arm 13 and from this extends downward a latch 82 with a hook 83 at the end preferably bevelled off at 84.

When this hook 83 is pulled out from under the dog 15, by the flexible member from the solenoid S, the dog drops by gravity to a position in front of the bunter 5 preferably being checked in the right position as by a check arm 85 and set screw 86 similar to the arm 18 and set screw 11 as shown by the dotted lines in Fig. 18.

As the lay and bunter move forward, as shown

in Figs. 19 and 20, the arm 81 attached to the dog holding arm 13 which is substantially parallel with the hammer head arm 12 is moving down with the hook or spring latch 82 while the dog 15 is remaining level or as shown in Fig. 20 moving a short distance up so that it slips along the bevelled surface 84 of the hook 83 until it is caught by the hook which at this time has been released by the solenoid, the dog therefore being reset by the dog controlling member O which includes parts 81, 82, 83, 84.

When the transfer spring 9 returns the transfer H to its usual position spring latch 82 carries dog 15 with it to the position shown by the full lines in Figs. 18 and 19 ready for the next transfer.

I claim:

1. In a bobbin-changing loom having a stationary frame and a movable lay, a bunter carried by the lay on the magazine side to engage the free end of a dog, a magazine holding two or more bobbins and including devices to hold a full bobbin for transfer, a shuttle box carried by the lay to be in position under the full bobbin holding means, bobbin transfer mechanism including a transfer hammer having an arm to engage said full bobbin and a dog holding arm, a weft feeler, said weft feeler being of the electrically operable type; a dog freely pivoted to the dog holding arm; a stop to check the dog in bunter engaging position; a dog controlling member carried by and movable with the transfer hammer, said member including spring actuated means to hold the dog out of the path of the bunter; and a solenoid in circuit with and energized by the weft feeler and including an armature and a connection from the armature to the spring actuated means to release the dog when the feeler indicates exhaustion and to allow the free end of the dog to move into the path of the bunter.

2. In a bobbin-changing loom having a stationary frame and a movable lay, a bunter carried by the lay on the magazine side to engage the free end of a dog, a magazine holding two or more bobbins and including devices to hold a full bobbin for transfer, a shuttle box carried by the lay to be in position under the full bobbin holding means, bobbin transfer hammer having an arm to engage said full bobbin and a dog holding arm, a weft feeler, said weft feeler being of the electrically operable type; a dog freely pivoted to the dog holding arm; a stop to check the dog in bunter engaging position; a dog controlling member carried by and movable with the dog holding arm, said member including spring actuated means to hold the dog out of the path of the bunter; and a solenoid in circuit with and energized by the weft feeler and including an armature and a connection from the armature to the spring actuated means to release the dog when the feeler indicates exhaustion and to allow the free end of the dog to move into the path of the bunter.

3. In a bobbin-changing loom having a stationary frame and a movable lay, a bunter carried by the lay on the magazine side to engage the free end of a dog, a magazine holding two or more bobbins and including devices to hold a full bobbin for transfer, a shuttle box carried by the lay to be in position under the full bobbin holding means, bobbin transfer mechanism including a transfer hammer having an arm to engage said full bobbin and a dog holding arm, a weft feeler, said weft feeler being of the electrically operable type; a dog shaft carried by the

dog holding arm and a dog freely pivoted on said dog shaft; a stop to check the dog in bunter engaging position; a dog controlling member carried by and movable with the bobbin transfer hammer, said member including a spring pressed dog holding part to hold the dog out of the path of the bunter; and a solenoid in circuit with and energized by the weft feeler and including an armature and a connection from the armature to the dog holding part to release the dog when the feeler indicates exhaustion and to allow the free end of the dog to move into the path of the bunter.

4. In a bobbin-changing loom having a stationary frame and a movable lay, a bunter carried by the lay on the magazine side to engage the free end of a dog, a magazine holding two or more bobbins and including devices to hold a full bobbin for transfer, a shuttle box carried by the lay to be in position under the full bobbin holding means, bobbin transfer mechanism including a transfer hammer having an arm to engage said full bobbin and a dog holding arm, a weft feeler, said weft feeler being of the electrically operable type; a dog shaft carried by the dog holding arm and a dog freely pivoted on said dog shaft; a stop to check the dog in bunter engaging position; a dog controlling member carried by and movable with the dog holding arm, said member including a spring pressed dog holding pin to hold the dog out of the path of the bunter; and a solenoid in circuit with and energized by the weft feeler and including an armature and a connection from the armature to the dog holding pin of the controlling member, to release the dog when the feeler indicates exhaustion and to allow the free end of the dog to move into the path of the bunter.

5. A device of the character described in claim 4 in which the dog controlling member and dog are separately movable and are connected by spring means; and resetting means for the dog controlling member.

6. A device of the character described in claim 4 in which the dog controlling member and dog are separately movable, the dog controlling member having a dog lifting arm; a spring to so move the dog controlling member that its dog lifting arm lifts the dog so that its free end is in the path of the bunter; and resetting means for the dog controlling member.

7. In a bobbin-changing loom having a stationary frame and a movable lay, a bunter carried by the lay on the magazine side to engage the free end of a dog; a reserve bobbin magazine holding two or more bobbins and including devices to hold a full bobbin for transfer, a shuttle box carried by the lay to be in position under the full bobbin holding means, a bunter on the lay, bobbin transfer mechanism including a transfer hammer with an arm to engage said bobbin and a dog holding arm, a weft feeler, said weft feeler being of the electrically operable type; a dog shaft carried by the dog holding arm; a dog freely pivoted on said dog shaft; a stop to stop the dog in bunter engaging position; a dog controlling member carried by and movable with the dog shaft, said member including a holding pin arm through which is a holding pin hole, a spring connecting it with the dog and a resetting arm movable with the holding pin arm; a spring pressed dog holding pin passing through said holding pin hole and projecting therefrom when free to engage the transfer hammer dog arm to hold the dog out of the path of the bunter; and

8. In a bobbin-changing loom having a stationary frame and a movable lay, a bunter carried by the lay on the magazine side to engage the free end of a dog, a magazine holding two or more bobbins and including devices to hold a full bobbin for transfer, a shuttle box carried by the lay to be in position under the full bobbin holding means, bobbin transfer mechanism including a transfer hammer having an arm to engage said full bobbin and a dog holding arm, a weft feeler, said weft feeler being of the electrically operable type; a dog shaft carried by the

a solenoid in circuit with and energized by the weft feeler and including an armature and a flexible connection from the armature to the dog holding pin to release that pin from the dog arm when the feeler indicates exhaustion to allow the free end of the dog to move into the path of the bunter; and a resetting stop fixed to the frame to engage the resetting arm of the dog controlling member when the bunter moves the dog arm of the transfer towards the front of the loom.

8. In a bobbin-changing loom having a stationary frame and a movable lay, a bunter carried by the lay on the magazine side to engage the free end of a dog; a stationary reserve bobbin magazine holding two or more vertical stacks of bobbins and including devices to hold a full bobbin for transfer, a shuttle box carried by the lay to be in position under the full bobbin holding means, a bunter on the lay, bobbin transfer mechanism including a transfer hammer with an arm to engage said bobbin and a dog holding arm, a weft feeler, said weft feeler being of the electrically operable type; a dog shaft carried by the dog holding arm; a dog freely pivoted on said dog shaft; a stop to stop the dog in bunter engaging position; a dog controlling member carried by and movable with the dog shaft, said member including a holding pin arm through which is a holding pin hole, a dog moving arm and a resetting arm movable with the holding pin arm; an engaging spring connected to the

controlling member for moving it and with it the dog moving arm and the free end of the dog into the path of the bunter; a spring pressed dog holding pin passing through said holding pin hole and projecting therefrom when free to engage the transfer hammer dog arm to hold the dog out of the path of the bunter; and a solenoid in circuit with and energized by the weft feeler and including an armature and a flexible connection from the armature to the dog holding pin to release that pin from the dog arm when the feeler indicates exhaustion, whereby the dog is moved by the engaging spring and the dog controlling member so that the free end of the dog is in the path of the bunter; and a resetting stop fixed to the frame to engage the resetting arm of the dog controlling member when the bunter moves the dog arm of the transfer towards the front of the loom.
